United States Patent Office

Des. 175,841
Patented Oct. 18, 1955

175,841

CAP

Morris Kean, University City, Mo.

Application February 7, 1955, Serial No. 34,394

Term of patent 14 years

(Cl. D3—13)

FIG. 1

FIG. 2

FIG. 3

Fig. 1 is a side view of a cap showing my new design;

Fig. 2 is a rear view thereof as it appears with the rain shield folded up; and

Fig. 3 is a top view thereof as it appears with the rain shield and muffler folded up.

I claim:

The ornamental design for a cap, substantially as shown.
